H. RACHMANN.
ATOMIZER FOR SCENT AND OTHER SPRAYS.
APPLICATION FILED MAY 31, 1907.

UNITED STATES PATENT OFFICE.

HENRY RACHMANN, OF HAIDA, AUSTRIA-HUNGARY.

ATOMIZER FOR SCENT AND OTHER SPRAYS.

No. 904,149.

Specification of Letters Patent.

Patented Nov. 17, 1908.

Application filed May 31, 1907. Serial No. 376,470.

To all whom it may concern:

Be it known that I, HENRY RACHMANN, a subject of the Emperor of Austria-Hungary, residing at Haida, Kingdom of Bohemia, and Empire of Austria-Hungary, have invented certain new and useful Improvements in Atomizers for Scent and other Sprays, of which the following is a specification.

10 My invention relates to atomizers especially those for hand use, of the hollow-reciprocating piston form, and my invention consists in substance of a valved pump barrel or cylinder which has inserted thereon a hollow piston-rod provided at the outer end with a valved head, having a suitable nozzle provided with a suitable atomizing cap or tip, and by the peculiar construction of the nozzle and cap or tip, the fine stream of liquid just before it issues from the cap or tip is given a cyclonic or whirling spiral motion.

25 My said invention is fully shown in the following specification of which the accompanying drawing forms a part, and wherein the sole figure is a view thereof in central vertical section.

In the drawing the letter *a* indicates a pump tube or barrel, the lower end *b* is reduced in diameter and formed separately from the body to which it is connected by a screw thread *c*. The upper end of the barrel *a* is enlarged and may be provided with an exterior screw thread *d* whereby it may 35 be attached to the cap *e* cemented or otherwise secured to the neck of the flask *F*.

The reference letter *g* indicates a cap or enlarged portion of the pump-barrel *a* closing the opening in the cap *e*. The cap *g* 40 being centrally perforated for the passage of a hollow piston rod *h*, and its upper part forming a stuffing box or gland-packing *g'*, closed by a screw cap *g''*, for the piston rod *h*. The piston rod *h* is provided at its lower end with a hollow piston *i* preferably composed of two cup leathers as shown. The upper end of the piston rod *h* has secured to it in any suitable manner a head *k* of any 45 convenient outline to which is connected by a screw thread or the like a discharge nozzle *l*, terminating in an atomizing tip *m* having at the extreme tip a small central perforation through which the spray issues.

50 That portion of the outer end of the discharge nozzle *l*, covered by the tip *m* is closed at the end adjacent to the outlet of

the tip; and a short space is left between the inner face of the end wall of the tip and the outer face of the end wall of the discharge nozzle *l*; and the communication with this space at the outer end is a spiral groove *m'*, on the outside of the nozzle which groove is in communication with the interior of the nozzle *l*, at its other end by a suitable perforation *m''*. In passing through this spiral groove *m'* the liquid which is to be reduced to spray, before being blown out through the central opening *m*, is given a twist or cyclonic spiral whirling motion, and by this a far better atomization and a finer spray of the liquid at its escape from the nozzle is accomplished.

The reference letter *n* indicates the inlet valve located at the point of juncture between the barrel *a* and its lower end *b*, and provided with a spring *N'* so as to keep it upon its seat; and a second valve *o* is disposed within the part *k* at the point of juncture with the nozzle *l* and is provided with a spring *N''* for keeping it upon its seat.

55 The action of the device is as follows: The upper end of the piston rod *h* is grasped by the fingers and reciprocated, the liquid issuing from the perforation in the cap *m*. Upon pulling the piston rod upwards liquid is drawn into the barrel past the valve *n* filling said barrel. The valve *o* during this movement being pressed against its seat. Upon the downward movement the valve *n* is pressed upon its seat and the fluid in the barrel is forced up the hollow piston rod lifting the valve *o* from its seat and finally escaping through the perforated cap *m* as described. A sleeve *r* may be provided upon the rod *h* to limit its upward movement.

95 Although I have described the device as an atomizer for scent or other sprays it will be evident that it may be readily adapted for other uses. For example by simply removing the atomizing tip *m* it may be employed for with-drawing liquids from bottles, and discharging same into glass or other receptacles.

100 What I claim as my invention and desire to secure by Letters Patent, is—

105 1. In an atomizer, a barrel adapted for attachment to the neck of a flask, a hollow piston rod movable therein, a hollow piston at the lower end of the piston rod, a hollow discharge-nozzle at the upper end of said piston rod, closed at the extreme outer end, and provided with an exterior peripheral spiral

groove the inner end of which is in communication by way of a perforation with the interior of the nozzle, the other end extending to the outer end of the nozzle, and a perforated 5 cap or atomizing-tip covering the grooved end of the nozzle.

2. In an atomizer, a barrel adapted for attachment to the neck of a flask, a hollow piston rod movable therein, a hollow piston at 10 the lower end of the piston-rod, a hollow discharge nozzle at the upper end of said piston rod closed at the outer end, a spiral groove formed on the periphery of the nozzle at the outer end the inner end of which 15 groove communicates with the interior of the nozzle while the outer end terminates at the outer end of the nozzle, and a perforated cap or atomizing-tip covering the grooved end of the nozzle.
- 20 3. In a device of the class described, a hollow discharge nozzle having an end-wall at the outer end, an atomizing tip having a central perforation in the end wall covering the nozzle in such manner that a small-space or 25 whirl-chamber is left between such two end

walls, a perforation formed in the peripheral wall of the nozzle adjacent to the end, and a spiral groove formed on the periphery of the nozzle wall forming a communication between the perforation and the whirl-chamber 30 when the tip is in position on the nozzle.

4. In a device of the class described, a hollow discharge nozzle having an end-wall at the outer end, an atomizing-tip having a central perforation in the end wall covering the 35 nozzle in such manner that a small-space or whirl-chamber is left between such two end walls, a perforation formed in the periphery wall of the nozzle adjacent to the end, and a spiral groove forming a communication between the perforation and the whirl-chamber 40 when the tip is in position on the nozzle.

In testimony whereof I have signed my name to this specification in the presence of two subscribing witnesses.

HARRY RACHMANN.
